UNITED STATES PATENT OFFICE.

JOHN KEATS, OF BAGNALL, AND WILLIAM STEPHENS CLARK, OF STREET,
ENGLAND.

SOLE-PREPARING MACHINE.

SPECIFICATION forming part of Letters Patent No. 651,042, dated June 5, 1900.

Application filed September 10, 1897. Serial No. 651,162. (No model.)

To all whom it may concern:

Be it known that we, JOHN KEATS, of Bagnall, near Stoke-upon-Trent, county of Stafford, and WILLIAM STEPHENS CLARK, of Street, county of Somerset, England, have invented a certain new and Improved Machine for Preparing Soles for Boot and Shoe Manufacture, of which the following is a specification.

10 This invention has for its object an improved machine for so preparing boot and shoe soles that when the uppers are sewed to the soles a close and practically water-tight joint will be obtained. The machine is intended to produce near the edge of the sole and at any desired distance therefrom a raised portion, forming a rib, to which the upper may be subsequently sewed. By reason of this raised portion which we obtain by means of our machine the upper is not sewed flat to the sole, but vertically against the raised rib.

To make the following description as clear as possible, we have represented our improved machine in the accompanying drawings.

25 Figure 1 is a side elevation of the improved machine. Fig. 2 is a plan view, and Fig. 3 is an end view, of the same. Fig. 4 is an enlarged view of the operating parts of the machine with a sole under treatment. Fig. 5 is a partial plan view of the machine, certain parts being removed to bring into view underlying portions of the machine. Fig. 6 is a partial end view, portions of the mechanism being removed to render more clear the constructions of the remaining parts. Fig. 7 is a detached view of the mechanism for operating the driver. Fig. 8 shows a leather sole, and Fig. 9 a felt sole, after passing through the machine.

40 Mounted in bearings in the frame A is the driving-shaft H of the machine, which receives its movement from hand or other motive power. This shaft H has keyed to it at its left-hand extremity a coned roller T, having a slightly-swelled portion or bead at t. This roller T serves to support the sole during the operation of molding the rib which is to receive the stitches and to impart a traversing motion to the sole through the machine.

45 50 In front of the coned roller T (see Fig. 1)

is an adjustable support Q for guiding the sole to the roller. This support Q is secured to the frame A by a clamping-screw q, which passes through an elongated hole q' in the support Q and enters a tapped hole in the 55 frame.

Keyed to the shaft H is a conical-toothed wheel I, which engages with a similar conical-toothed wheel K, keyed on the end of a shaft G, which has its bearings in a rocking frame 60 B. This shaft G lies, when in its acting position, at an angle of some thirty degrees, or thereabout, to the horizontal shaft H for the purpose to be presently explained. The shaft G has fixed upon its left-hand end (see Fig. 65 1) a pressing-roller G', formed with two annular ribs, the outer one of which is milled to take a good hold of the work. This roller G', with the roller T, assists in molding the sole and feeding it forward while under treatment. 70

Upon the shaft G is keyed a bevel-wheel L, which engages with bevel-wheel M, carried by a short vertical shaft M'. On this shaft M' is also keyed a spur-wheel N. This wheel N engages with the wheel O on a shaft O', 75 which carries at its upper end a block F, fitted with a crank-pin F'. This crank-pin is adjustable in a radial groove in the block by means of a traversing screw a. (See Figs. 5 and 7.)

80 E is a square-ended rod formed with an eye which fits over the crank-pin F' and is secured by a nut F''. By this connection of the rod E with the crank-pin, it will at each rotation of the wheel O receive a rapid to-and-fro movement in the direction of its length and be driven into contact with the sole for the purpose of molding the marginal rib thereon. This rod E, as will be seen hereinafter, constitutes the chief acting part of the 85 machine, and it is controlled in its movements by a radius arm R, pivoted to a lug on the adjustable guide P. (See Fig. 5.)

The rocking frame B, which carries the shaft G, is supported on screwed centers B', 95 projecting inward from the opposite sides of the frame A, and it receives a tendency to rise from a strong spring S, actuating and underlying a rock-lever R' (see Fig. 6) for the purpose of lifting the pressing-roller G' 100

and holding it off the work, as shown in the dotted position at Fig. 4.

Upon the frame A is fulerumed a hooked lever C, from which depends a rod C', connected at its lower end to a pedal operated by the foot of the workman. This hooked lever C overlies and bears upon a vertical piece D, carried by the movable frame B. Normally when the workman is not pressing upon the pedal the pressing-roller G' of the shaft G will retain the dotted position of Fig. 4; but when the workman presses on the pedal connected to the rod C' the hooked lever C causes the depression of the roller G' and the gripping of the work firmly between it and the roller T.

Having thus described the parts which constitute our improved machine, we will now describe its action; but we would first remark that the work which it is intended to perform is to produce the raised vertical portion or rib indicated on the sole at X, Fig. 5. It is to this raised rib that the edge of the upper after it is made up is sewed either by hand or machinery.

The leather sole to be treated may be slit for a slight depth on its edge by any appropriate instrument. This done the workman, using the guide Q as a point of support, introduces the sole between the roller G' and the cone T, placing it so that the grip of the roller G' may gage the finishing-point of the raised rib. At this moment he presses on the pedal, so as to bring the roller G' down upon the sole, which is thus tightly gripped between it and the cone T. The workman then sets the machine in motion. Consequent upon the rotation of the gripping-rollers the sole is drawn in and the workman holding it there with his hands guides it while the roller G' describes a line around the sole equidistant from its edge, pressing down the leather, so as to mold the inner side of the rib at its base to correspond with the angle formed between the bead *t* of the conical roller T and the end of the pressing-roller G'. The exact lateral position of the sole with respect to the feed-rollers is determined by the adjustable guide P, secured to the guiding-support Q. During the feeding forward of the sole under the action of the roller G' and the cone T the rod E, which may be termed the "rib-former," moves with an oscillating backward-and-forward motion under the influence of its revolving crank-pin and repeatedly and violently strikes the edge of the raised portion of the sole against the inner end of the roller G' and molds it into a raised rib. By reason of the oscillatory movement of this rod, caused by its connection with the radius-arm R, it does not strike directly against the rib, but rather tangentially, thus aiding in the feeding of the sole. Under these conditions it will be understood that it is necessary that the rapidity of the oscillatory movement of the rod E shall be such that its end when in contact with the leather shall move forward at the same rate

as the feed-rollers, as otherwise the leather will be torn. Again, as the rod E leaves the sole for a certain period of time to retire it is necessary that its acting end should have a sufficiently-broad surface to strike all points of the raised rib in a uniform manner several times. The rapidity of movement of the rod E depends, naturally, upon the relative proportions of the gears which control the revolution of the crank-pin connected to the rod, and we therefore reserve the right to modify the gears according to the material of which the sole may be made. When the workman after having guided the sole by hand comes to the terminating-point of the course—that is to say, to the place where the raised rib shall cease—he releases the pedal, the shaft G rises, and he can then easily withdraw the sole from the machine.

The required depth and position of the raised rib to be produced by the machine depend, naturally, upon the mode of attaching the upper to the sole and will vary according to its shape.

Our machine will manufacture soles of felt or leather, as above stated, and the pressure and the form of the roller G' and the length of travel of the rod E may vary according to the nature of the material employed. These are the only alterations necessary to suit the work. All other parts remain the same whatever may be the material employed.

As the thickness of the sole under treatment varies, the adjustment of the height of the rod E must also vary. For this purpose the rod is passed through the adjustable guide P, which is capable of being raised or lowered. Furthermore, this guide P by reason of its attachment to the support Q admits of slight lateral adjustment to suit the varying width of the flanged portion of the sole.

In the case of felt soles we do not split the edge first, it being unnecessary to do this to obtain the raised rib; but we heat the roller G' and the pushing instrument or rib-former E, so that when the rib is molded the heated pressure causes it to retain its rib or guide line shape.

We disclaim, in a lip-turning machine, the combination, with a reciprocating lip-setting tool, of means to so actuate said tool and to support the work, so as to cause said tool to strike and act upon the lip at the base thereof within the angle formed by the lip and feather of the insole; in a lip-turning machine, the combination, with a work-support, of a reciprocating lip-setting tool movable in a plane inclined to the surface of the work-support; in a lip-turning machine, the combination, with a reciprocating lip-setting tool, of clamping means arranged to hold the insole against the action of said tool; in a lip-turning machine, the combination, with a reciprocating lip-setting tool, of a presser-foot arranged to hold the insole during the operation of said tool; in a lip-turning machine,

the combination, with a reciprocating lip-setting tool, of a work-support and means to clamp the insole against said work-support during the operation of said tool; in a lip-
 5 turning machine, the combination, with a reciprocating lip-setting tool, of a clamping device and connected mechanism for actuating said tool and clamping device; in a lip-turning machine, the combination, with a recip-
 10 roating lip-setting tool, of a clamping presser-foot and connected mechanism for actuating said tool and foot; in a lip-turning machine, the combination, with a reciprocating lip-setting tool, of a clamping presser-foot and
 15 means for simultaneously actuating said tool and presser-foot, and in a lip-turning machine, the combination, with a reciprocating lip-setting tool, of clamping means engaging the sole-surface within the lip to hold the sole
 20 against the action of said tool, as our machine is essentially a rib-molding or rib-forming machine as distinguished from a machine for turning up a lip and subsequently fixing the upturned lip in its position.

25 What we claim is—

1. The machinery above described for raising a marginal rib on boot and shoe soles, such machinery consisting in a pair of driven gripping and feeding rollers arranged one above the other and the lower one of which is coned, fixed bearings in which said lower roller is supported to form a bed for the work, a suspended rocking frame in which the shaft of the upper roller is supported in an inclined position, a reciprocating rib-former having a movement transverse to the rotation of said rollers, and means for drawing down said rocking frame for securing the work in the grip of the rollers and for supporting it against the action of the rib-former, all in combination substantially as herein described.
2. In combination with a reciprocating rib-former a pair of gripping and feeding rolls the lower one of which is conical and is formed with an annular bead at its base while the upper roller is mounted in relation to the lower roller so that said upper roller will bite the work raised by the bead of the lower roller at a point which gages the base at the inner 50 side of the rib which upper roller serves as a

support for the rib while under the action of the rib-former.

3. The combination with a pair of gripping-rolls for feeding a sole and a reciprocating rib-former having a movement transverse to the rotation of said rolls for the raising of a rib, of the support for guiding the sole to said rolls and a guide adjustable transversely to the rotation of said rolls for determining the position of the rib upon the sole, substantially as herein described.

4. The combination with the gripping and the feeding-rolls arranged one above the other and the reciprocating rib-former arranged transversely to the rotation of said rolls, of a vertical rotating shaft, a crank-pin carried by said shaft for producing the reciprocating movement of said former, a guide for the former which is vertically adjustable for the purpose of raising and lowering said former, and a radius-arm pivoted at a fixed point and connected with said former to permit its following the forward movement of the work and to assist in the feeding operation of the rolls, substantially as herein described.

5. The combination with a sole-support, of a combined feed and sole holding device arranged to engage the sole on the opposite side from its support and at a point inwardly from the position which the rib is to occupy, and a reciprocating rib forming or molding device arranged to move toward and away from said combined feed and sole holding device to form the rib, substantially as set forth.

6. The combination with a work-support and a rotary rib-molding device arranged to engage the sole at a point inwardly from the rib-line, of a rib-former arranged to force the upper portion of the outer margin of the sole toward the said rib-molding device, substantially as set forth.
